Primary Examiner — Marianne Pandozzi*(74) Attorney, Agent, or Firm* — Lempia Summerfield Katz, LLC(57) **CLAIM**

The ornamental design for a “pour spout,” as shown and described.

DESCRIPTION

FIG. 1 is a top, front and right side perspective view of my new design for a pour spout.

FIG. 2 is a right side view of the pour spout of FIG. 1.

FIG. 3 is a left side view of the pour spout of FIG. 1.

FIG. 4 is a front view of the pour spout of FIG. 1.

FIG. 5 is a rear view of the pour spout of FIG. 1.

FIG. 6 is a top view of the pour spout of FIG. 1.

FIG. 7 is a bottom view of the pour spout of FIG. 1.

FIG. 8 is an enlarged cross sectional view taken along line **8-8** of FIG. 7 broken away for ease of illustration;

FIG. 9 is a perspective view of FIG. 1 with the lid in open position; and,

FIG. 10 is a top front right side perspective view showing a second embodiment of my new design, all sides being identical to FIGS. 1-9 save the for transparency of the spout tube.

1 Claim, 5 Drawing Sheets---
